UNITED STATES PATENT OFFICE.

WILLIAM L. DODGE, OF EAST SOMERVILLE, MASSACHUSETTS.

GAGE FOR CUTTER-HEADS.

SPECIFICATION forming part of Letters Patent No. 269,025, dated December 12, 1882.

Application filed February 13, 1882. (No model.)

To all whom it may concern:

Be it known that I, WILLIAM L. DODGE, of East Somerville, in the county of Middlesex, of the State of Massachusetts, have invented 5 a new and useful Improvement in Mechanism for Manufacturing Moldings; and I do hereby declare the same to be described in the following specification and represented in the accompanying drawings, of which—
10 Figure 1 is a vertical and transverse section, and Fig. 2 a horizontal and transverse section, of the cutters, cutter-heads, and their shaft of what is usually termed a "variety molding machine," such heads and shaft being provided
15 with my invention. Fig. 3 is an edge view, and Fig. 4 a bottom view, of the cutter guards or fenders and their supporting-hub, to be described.

The improvement in question is not only for 20 regulating the depth of cut of each cutter while it is in operation, but to prevent it from taking too deep or rank a cut into the wood, and thereby suddenly driving against it (the said cutter) the hand of the attendant and inflicting there-
25 on serious injury, such an accident having been met with by the undersigned while employed in making moldings by a machine of the kind above mentioned.

The improvement consists mainly in the com- 30 bination of an adjustable guard and a supporting device or devices therefor with each of the cutters and its supports and shaft, all being essentially as described and represented.

In the drawings, A denotes the driving shaft 35 or arbor of the cutters of a machine for "stick-
ing" or forming moldings. B B are two cutters, applied to such shaft in the ordinary manner—that is, by two disks or heads, C D, en-
compassing the shaft, and grooved to receive
40 the cutters at their opposite horizontal parallel edges, and held in place by a screw, a, and nut b, arranged as shown. On the shaft, and be-
tween the two cutters, is a hub, E, provided
with a clamping-screw, e, to fix it to the shaft.
45 It also has two wings or flat projections, d,

extending from it, as shown. Upon each of the said wings and against each of the cutters, at its upper edge, is a flat fender or guard, G, which has in it at its inner end a curved notch, e, to receive the shaft. The outer end of this guard is curved, as shown at i, to the arc of a circle having a radius whose center is in or about in the axis of the hub. Each of the guards is fastened to the sustaining-wings by a set-screw, f, that goes through a slot, g, in the wing and screws into the guard, all being as shown. The guards, when arranged with the cutters in manner as represented in Figs. 1 and 2, can be adjusted so as to gage the thickness of shaving made by each cutter while it is in operation. Each guard has in it, between its curved bearing-edge i and the cutting-edge of the cutter, to which the said guard is applied, a notch, k, the object of which is to prevent slivers or fibers of the wood from becoming 65 caught and jammed between the guard and the cutter, so as to interfere with the proper operation of the latter. A stick or molding-blank, while being reduced by the cutters, is main-
tained by the guards in its proper relations to 70 the said cutters, and cannot be caught by either of them so as to be suddenly drawn inward in a manner to bring against a cutter the hand of an attendant who may have hold of such stick. The guard is arranged at the upper part only 75 of each cutter, and does not extend down along the entire cutting-edge of the said cutter, the shavings being thereby free to escape without hindrance from the guards.

I claim—

In combination with the molding-machine cutters, their supporting-heads and driving-
shaft, the adjustable guards, and their sus-
taining winged hub, adapted to the said shaft
and cutters, substantially and for the pur- 85
poses as set forth.

WILLIAM L. DODGE.
